CLAIM

The ornamental design for a mobile chassis portion of a pressure washer, as shown and described.

DESCRIPTION

FIG. 1 is an isometric view of a mobile chassis portion of a pressure washer;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom isometric view thereof.

The dashed lines in the Figures depict portions of the mobile chassis portion of a pressure washer that form no part of the claimed design.

1 Claim, 8 Drawing Sheets
